UNITED STATES PATENT OFFICE.

LEOPOLD MAMBOURG, OF COLUMBUS, OHIO, ASSIGNOR TO THE SANITARY NURSING BOTTLE COMPANY, OF COLUMBUS, OHIO.

NURSING-BOTTLE.

1,080,070.

Specification of Letters Patent.

Patented Dec. 2, 1913.

Application filed February 2, 1912. Serial No. 675,021.

To all whom it may concern:

Be it known that I, LEOPOLD MAMBOURG, a citizen of the United States, residing at Columbus, Franklin county, Ohio, have invented certain new and useful Improvements in Nursing-Bottles, of which the following is a specification:

This invention pertains to improvements in nursing bottles having bottom seals, the improvements being designed to facilitate the efficient and sanitary sealing of the base of the bottle, to facilitate the unsealing of the bottle, and to prevent undesired rolling of the bottle, and the improvements will be readily understood from the following description taken in connection with the accompanying drawing in which:

Figure 1 is a side elevation of a nursing bottle exemplifying my present improvements: Fig. 2 a vertical diametrical section of the bottle proper: Fig. 3 a vertical diametrical section of the bottom cap and vent-tube: Fig. 4 is a plan of the bottom cap and vent-tube: and Fig. 5 a vertical diametrical section, on a much enlarged scale, through a portion of the sealing joint between the bottle proper and the bottom cap.

In the drawing:—1, indicates the bottle proper, the same being preferably circular in plan: 2, the nipple on the mouth of the bottle: 3, an externally threaded boss projecting concentrically from the base of the bottle: 4, a flat annular shoulder surrounding the threaded boss: 5, a threaded metallic cap adapted to be screwed upon the threaded boss of the bottle: 6, a flat flange forming the rim of the cap: 7, an open-bottomed vent-tube projecting from the cap up into the bottle to a point near the neck of the bottle: 8, a small venting aperture in the upper end of the vent-tube: 9, a gasket, of elastic material, disposed between the flat flange 6 of the cap and the flat annular shoulder 4 of the bottle, the thickness of this gasket being such that the threaded boss of the bottle cannot bottom in the cap: 10, lugs projecting outwardly from the periphery of the cap: and 11, a large opening through the threaded boss of the bottle.

The opening 11 through the threaded base of the bottle is of large size, and the bore of the base of the bottle, above the

bottom of the bottle, joins the bore of the opening 11 by a contour contracting inwardly without any outward grooving of the base of the bore of the bottle. By this construction, taken in connection with the mouth of the bottle, the bottle may be readily cleaned by passing water freely through it, the inwall of the bottle being free from grooves or recesses. The gasket, being compressed between the bottle-shoulder and flange 6 of the cap, effects a sealing between the cap and the bottle and is as far as possible removed from the contents of the bottle, thus avoiding, as far as possible, any deteriorating effect of the contents of the bottle upon the gasket, or contaminating influence of the material of the gasket upon the contents of the bottle. When the cap, together with the vent-tube carried by it, is unscrewed and removed from the bottle, the gasket is exposed upon the exterior or the threaded base where it may be readily cleaned, and, if need be, the gasket may be readily removed from the threaded base for more perfect cleaning or for replacement in case of damage. The lugs 10, of which there may be any desired number, facilitate the screwing and unscrewing of the cap and prevent undesired rolling of the bottle upon a flat surface.

The vent tube 7 integrally formed with the cap 5 is of quite large diameter so that it may be easily cleaned by means of a brush or swab inserted from the outer end. This cleaning is not possible in cases where vent tubes of small diameter are provided. The sheet-metal construction of the cap and tube permit the tube to be made of ample diameter and sufficient strength. The relatively large tube terminates in an inwardly tapered portion provided with a relatively small vent opening.

I claim:

In a nursing bottle or the like, the combination of a bottle body having a base opening, an external screw-thread surrounding the opening and a circular outwardly extending shoulder at the base of said thread, a closure for the opening consisting of a sheet-metal cap having an internal thread to engage the bottle thread, an outwardly extending flange at the inward end of said

thread, said cap flange being opposed to said bottle shoulder, said closure also having an integrally formed tube of relatively large diameter extending within the bottle and terminating in a relatively small vent opening, said closure also being provided at the outward end of its screw-threaded portion with one or more lateral projections to pro-

vide a fastening grip and prevent rolling, and a gasket between the closure flange and 10 the bottle shoulder.

LEOPOLD MAMBOURG.
